ADJUSTABLE HOLDER FOR COMPRESSIBLE
CLEANING MATERIALS

Daniel D. Wolfe, Dayton, Ohio.

Application June 17, 1944, Serial No. 540,802

7 Claims. (Cl. 15—209)

1.

My invention relates to holders for cleansing materials, and particularly for compressible masses of cleansing material, such as steel wool, sponge, metal fabric, or sponge rubber pads, my invention being particularly adapted for use with masses of steel wool.

It is a purpose of my invention to provide a device of the above mentioned character, which is provided with a handle, and means for holding a mass of such material as steel wool, for example, projecting beyond said handle, said means being adjustable to hold said mass of steel wool or similar material fixed to said handle so that the steel wool or similar abrasive material can be readily manipulated by means of the handle to scour or cleanse the cooking utensil or similar member that is to be operated upon by the steel wool or similar material held by my improved holder.

It is particularly a purpose of my invention to provide a device of the above mentioned character, which is so constructed and arranged that various size masses of said steel wool or similar material can be held thereby effectively. In order to accomplish this purpose, the holding means is made adjustable and is so made that it will remain in adjusted position to firmly grip the compressible material and hold it substantially in fixed position relative to the handle. Said gripping means is, preferably, so constructed and arranged that when in adjusted position to firmly grip the mass of steel wool or similar material held thereby, the steel wool or similar compressible material will project from the holding means both endwise and laterally so that the holding members or fingers will not engage the member that is to be cleansed, but only the cleansing material, such as the steel wool, will engage said member.

My improved adjustable holder comprises a plurality of fingers, which together comprise a cage-like housing for the compressible cleansing material, such as steel wool, said fingers, when the same are adjusted to compress the material and hold the same in position that said fingers will be buried or embedded in the material, whereby portions of the mass of material will protrude or project between said fingers, thus preventing the fingers from engaging with the object that is being scoured or cleansed by the steel wool, or similar compressible material.

More particularly my invention comprises a holder comprising a handle portion having fingers projecting endwise therefrom, which are swingingly mounted relative to said handle so as to

2.

be movable toward and away from the axis of said handle, and which are provided with means for adjusting the same toward and away from each other and for holding the same in any adjusted position thereof, comprising self-locking means for moving the adjusting means to the position desired for the adjustment of the fingers to either grip the material therebetween or release the material as may be desired. It is desirable to provide means for releasing the material or spreading the fingers apart to insert a new mass of such compressible cleansing material as steel wool, within the receptacle formed collectively by said fingers, or to pull some of the mass of material out axially away from the handle to project endwise beyond the fingers to provide a mass thereof which will readily engage with the surface of a utensil to be cleansed or abraded thereby.

Other objects and advantages of my invention will appear as the description of the drawings proceeds. I desire to have it understood, however, that I do not intend to limit myself to the particular details shown or described, except as defined in the claims.

In the drawings:

Fig. 1 is an elevational view of my adjustable handle, showing a wad or pad of compressible cleansing material, such as steel wool, mounted in position therein.

Fig. 2 is a fragmentary longitudinal sectional view through the adjustable holder shown in Fig. 1.

Fig. 3 is a section taken substantially on the line 3—3 of Fig. 2, and

Fig. 4 is a view similar to Fig. 2 of a modification.

Referring in detail to the drawings, in Fig. 1 is shown one form of my improved adjustable holder having a handle 5, which may be of any desired size and shape, found to be convenient for use and which is, preferably, made of wood or similar material. Said handle, preferably, has a reduced end portion 6 thereon, upon which is mounted a ring-like member 7, said ring-like member being fixed to the reduced end portion 6 of said handle by means of one or more pins 8, but being spaced from the outer surface of said reduced portion 6, so as to permit the hook-like end portions 9 of the fingers 10 to be mounted for swinging movement on the ring-like member 7 without interference of the end portions 6 of the handle with such swinging movement, said hook-like end portions 9 having the extremities 11 thereof hooked around said ring-like member

7 so as to prevent disengagement of said fingers 10 from the ring-like member 7.

Each of said fingers has an outwardly inclined portion 12 thereon, which curves slightly, but is gradually outwardly inclined, approaching a straight line, as will be obvious from Fig. 1 of the drawings. The outwardly inclined portions 12 of the fingers have gradually increasingly curved portions 13 which merge with the arcuate or curved hook-like end portions 14 on each of said fingers terminating in the inwardly directed prongs 15 at the end of each of said fingers. Each of said fingers is, preferably, V-shaped in cross section, as will be obvious from Fig. 3, thus providing substantially a central ridge or rib running lengthwise of each of said fingers at 16 so as to stiffen the same and prevent any bending thereof under the stresses to which the same are subjected during use.

Due to the loose connection between the hook-like ends 9 of said fingers and the ring-like member 7, the fingers will be swingingly mounted on the ends of the handle member 5 to project endwise therebeyond and collectively form a cage-like receptacle for the compressible material, such as the mass of steel wool 17 shown in Fig. 1. Means is provided for simultaneously moving the fingers 10 toward the axis of the handle 5, or away from the axis of the handle 5, as may be found desirable, to either compress the material 17 and firmly hold it to the handle, or to release the material so as to permit removal thereof, or open the cage-like receptacle to permit insertion of said material 17 within said cage-like receptacle. Said means for adjusting the position of said fingers 10 is, preferably, of such a character that the same can be readily adjusted without engagement of the operator's fingers with the material 17, which, particularly in the case of steel wool, is very undesirable, and which is furthermore preferably so constructed as to hold the fingers 10 in any adjusted position that the same assume.

The means for adjusting the fingers and holding the same in adjusted position comprises a disk-like member 18, which is provided with a plurality of openings 19 therein for receiving the outwardly inclined portions 12 of the fingers 10 slidably. Preferably, the disk-like member 18 is provided with a flange or rim portion 20 to stiffen the same. Said rim portion 20 may engage the outwardly inclined portions 12 of the fingers to force the same toward the axis of the handle 5 to compress the material between said fingers and embed said fingers in said material, although such engagement is not absolutely necessary. However, if any springing of the fingers under pressure occurs, such engagement of said flange may occur. Means is provided for moving the disk-like member 18 axially of the handle 5, said means, preferably, comprising a knob-like member 21 mounted upon the shaft-like member 22, being, preferably, fixed thereto by means of a pin 28 and being curved so as to form a rounded end portion on the holder of a cap-like character, merging with the curved side walls of the handle 5. Preferably, a screw-threaded member 23 is fixed to the shaft 22 by any suitable means, such as a pin 24, in such a manner that the shaft 22 is held against endwise movement in the handle 5 due to the cooperation of the knob 21 and the enlarged threaded member 23, and so that the parts 22 and 23 rotate together. The threaded member 23 has screw-threaded engagement with a screw-threaded opening in the cen-

ter of the disk-like member 18, as will be obvious from Fig. 2. As the disk-like member 18 will be held against rotation due to the collective action of the fingers 10 to resist such movement, rotation of the knob-like member 21 will rotate the shaft 22 and advance the disk-like member 18 along the screw-threaded member 23 either toward the handle 5 or away from the handle 5, dependent upon the direction of rotation of the knob-like member 21. Either the member 23 or 21 can be made integral with the shaft 22 if desired.

It will be obvious from the above description that the fingers 10 can be readily adjusted by movement of the disk-like member 18 by rotation of the knob-like member 21 on the handle to firmly grip and compress the steel wool or similar material 17 between the fingers 10, or to move said fingers apart to permit the material 17 to be pulled out of the receptacle therefor formed by said fingers, axially of the handle 5, and that said fingers will be held in adjusted position due to the interlocking relationship of the disk 18 therewith. It will be furthermore noted that the outwardly inclined portions 12 of said fingers act as cam members to move said fingers either toward or away from each other, dependent upon the direction of movement of the disk-like member 18.

Should it be found desirable to simplify the construction of the device to save on the cost of production thereof, it may be desirable to provide the adjusting means shown in Fig. 4, in which the handle 5' is provided with a screw-threaded opening therein, with which the screw-threaded shaft 22' engages. The disk-like member 18' engages the fingers 10 in the same manner as previously described, said fingers being of the same shape and similarly mounted on the reduced end portion 6' of the handle 5' as the fingers 10 in the form of the invention shown in Figs. 1 to 3, inclusive, and having the same contour or shape as said fingers 10 in the other form of the invention. The disk-like member 18' is constructed substantially in the same manner as the disk-like member 18 and functions in the same manner by movement axially of the handle 5', as does the disk-like member 18. Said disk-like member 18', is, however, mounted on the shaft-like member 22' so that said shaft-like member 22' is rotatable relative to said disk-like member 18', but said disk-like member 18' is movable axially with the shaft-like member 22' as a unit, this being accomplished by providing a reduced end portion 25 on said shaft-like member 22', providing a shoulder between which and the washer 26 the disk-like member 18' is mounted, said washer 26 being held between said disk-like member and the head 27 formed on the reduced end portion 25 of said shaft-like member 22'.

It will be obvious that if the shaft 22' is rotated by a knob-like member similar to that provided for the member 22, the shaft will travel endwise in the handle member 5' to move the reduced end portion 25 thereof either toward or away from the handle 5', dependent upon the direction of rotation of said shaft 22', thus either causing the fingers 10 to separate or to move toward each other to grip the material 17 therebetween, as in the form of the invention shown in Figs. 1 to 3, inclusive.

What I claim is:

1. A holder for use with a mass of compressible material, comprising an elongated handle

member, a plurality of circumferentially spaced arcuate rigid fingers mounted to project endwise beyond said handle member in a circular series in embracing relation to said material, and means for simultaneously moving said fingers toward the axis of said handle to compress said material and embed said fingers therein or away from said axis to release said material, said fingers collectively forming an annular cage-like container for said material, said means comprising a disk-like member having openings therein slidably receiving said fingers through which said fingers pass, and rotatable means extending through said handle member, said rotatable means being fixed against movement axially relative to one of said members and screw-threadedly connected with the other of said members to move said disk-like member lengthwise of said fingers upon rotation of said means to adjust the position of said disk-like member and fingers and to hold said disk-like member and fingers in any adjusted position thereof.

2. A holder for use with a mass of compressible material, comprising an elongated handle member, a plurality of spaced rigid fingers swingably mounted in an annular series about one end of said handle member to project endwise therebeyond, each of said fingers having an outwardly inclined portion extending from its mounting on said handle and a curved hook-like portion extending from said outwardly inclined portion terminating in a pronged end directed toward the axis of said handle member, and means for simultaneously moving said fingers toward the axis of said handle member to compress said material and embed said fingers therein or away from said axis to release said material, said fingers collectively forming an annular cage-like container for said material, said means comprising a disk-like member having an annular series of openings therein in which said outwardly inclined portions of said fingers are confined and slidably mounted, and rotatable means extending through said handle member, said rotatable means being fixed against movement axially relative to one of said members and screw-threadedly connected with the other of said members to move said disk-like member lengthwise of said fingers upon rotation of said means and to hold said disk-like member in position at any point along said outwardly inclined portions of said fingers.

3. A holder for use with a mass of compressible material, comprising an elongated handle, a plurality of circumferentially spaced arcuate rigid fingers mounted to project endwise beyond said handle in a circular series in embracing relation to said material, and means for simultaneously moving said fingers toward the axis of said handle to compress said material and embed said fingers therein or away from said axis to release said material, said fingers collectively forming an annular cage-like container for said material, said means comprising a disk-like member having openings therein slidably receiving said fingers to confine the same, and means for moving said disk-like member lengthwise of said fingers to adjust the position of said disk-like member and fingers and hold said member and fingers in any adjusted position thereof, comprising a rotatable knob-like member on said handle at the end thereof opposite that from which said fingers project, and means extending longitudinally through said handle and connected with said disk-like member to move the same

axially of said cage-like member upon rotation of said knob-like member.

4. A holder for use with a mass of compressible material, comprising an elongated handle, a plurality of circumferentially spaced fingers swingably mounted in an annular series about one end of said handle to project endwise therebeyond, each of said fingers having an outwardly inclined portion extending from its mounting on said handle and a curved hook-like portion extending from said outwardly inclined portion terminating in a pronged end directed toward the axis of said handle, and means for simultaneously moving said fingers toward the longitudinal axis of said handle to compress said material and embed said fingers therein or away from said axis to release said material, said fingers collectively forming an annular cage-like container for said material, said means comprising a disk-like member having slots therein in which said outwardly inclined portions of said fingers are slidably mounted, and means for moving said disk-like member lengthwise of said fingers and holding the same in position at any point along said outwardly inclined portions of said fingers, comprising a rotatable knob-like member on said handle at the end thereof opposite that from which said fingers project, and means extending longitudinally through said handle and connected with said disk-like member to move the same axially of said cage-like member upon rotation of said knob-like member.

5. A holder for use with a mass of compressible material, comprising an elongated handle, a plurality of circumferentially spaced arcuate fingers mounted to project endwise beyond said handle in a circular series in embracing relation to said material, and means for simultaneously moving said fingers toward the longitudinal axis of said handle to compress said material and embed said fingers therein or away from said axis to release said material, said fingers collectively forming an annular cage-like container for said material, said means comprising a disk-like member having an annular series of slots therein through which said fingers pass, and means for moving said disk-like member lengthwise of said fingers to adjust the position of said disk-like member and fingers and hold said member and fingers in any adjusted position thereof, comprising a rotatable knob-like member on said handle at the end thereof opposite that from which said fingers project, and means extending through said handle and connected with said disk-like member, comprising a screw-threaded member connected with said knob-like member to be rotated thereby and threadedly connected with said disk-like member to move said disk-like member axially away from said handle into said cage-like container upon rotation of said knob-like member in one direction and toward said handle upon rotation of said knob-like member in the opposite direction.

6. A holder for use with a mass of compressible material, comprising an elongated handle, a plurality of circumferentially spaced fingers swingably mounted in an annular series about one end of said handle to project endwise therebeyond, each of said fingers having an outwardly inclined portion extending from its mounting on said handle and a curved hook-like portion extending from said outwardly inclined portion terminating in a pronged end directed toward the axis of said handle, and means for simultaneously moving said fingers toward the longitudinal axis of said

handle to compress said material and embed said fingers therein or away from said axis to release said material, said fingers collectively forming an annular cage-like container for said material, said means comprising a disk-like member having an annular series of slots therein in which said outwardly inclined portions of said fingers are slidably mounted, and means for moving said disk-like member lengthwise of said fingers and holding the same in position at any point along said outwardly inclined portions of said fingers, comprising a rotatable knob-like member on said handle at the end thereof opposite that from which said fingers project, and means extending through said handle and connected with said disk-like member, comprising a screw-threaded member connected with said knob-like member to be rotated thereby and connected threadedly with said disk-like member to move said disk-like member axially away from said handle into said cage-like container upon rotation of said knob-like member in one direction and toward said handle upon rotation of said knob-like member in the opposite direction.

7. A holder for use with a mass of compressible material, comprising an elongated handle, a plurality of circumferentially spaced fingers swingably mounted in an annular series about one end of said handle to project endwise therebeyond, each of said fingers having an outwardly inclined portion extending from its mounting on said handle and a curved hook-like portion extending from said outwardly inclined portion terminating in a pronged end directed toward the longitudinal axis of said handle, and means for simultaneously moving said fingers toward the axis of said handle to compress said material and embed said fingers therein or away from said axis to release said material, said fingers col-

lectively forming an annular cage-like container for said material, said means comprising a disk-like member having openings therein in which said outwardly inclined portions of said fingers are slidably mounted, and means for moving said disk-like member lengthwise of said fingers and holding the same in position at any point along said outwardly inclined portions of said fingers, comprising a rotatable knob-like member on said handle at the end thereof opposite that from which said fingers project, a shaft rotatable with said knob-like member extending axially through said handle and projecting beyond the end of the same from which said fingers project, and means on said projecting end having a screw-threaded connection with said disk-like member.
